(57) **CLAIM**

The ornamental design for a bimini hardtop for watercraft, as shown and described.

DESCRIPTION

FIG. 1 is a top isometric view of a bimini hardtop for watercraft, suitable for being mounted on a boat;

FIG. 2 is a top plan view thereof;

FIG. 3 is a front elevational view thereof;

FIG. 4 is left side elevational view thereof;

FIG. 5 is a right side elevational view thereof mounted to an example watercraft;

FIG. 6 is a rear elevational view thereof, mounted to an example watercraft;

FIG. 7 is top isometric view thereof, mounted to an example tower structure for a watercraft;

FIG. 8 is a top isometric view thereof including a removable center portion, mounted to an example tower structure for a watercraft;

FIG. 9 is right side isometric view thereof in a fully deployed configurations, mounted to an example tower structure for a watercraft;

FIG. 10 is a right side isometric view thereof in a fully deployed configuration;

FIG. 11 is a right side isometric view thereof in a vertical, partially stowed configuration, mounted to an example tower structure for a watercraft;

FIG. 12 is a right side isometric view thereof in a vertical, partially stowed configuration;

FIG. 13 is a right side isometric view thereof in partially stowed configuration, mounted to an example tower structure for a watercraft;

FIG. 14 is a right side isometric view thereof in a partially stowed configuration;

FIG. 15 is a right side isometric view thereof in a fully stowed configuration, mounted to an example tower structure for a watercraft; and,

FIG. 16 is a right side isometric view thereof in a fully stowed configuration.

The broken lines represent portions of the article that form no part of the claimed design.
